UNITED STATES PATENT OFFICE.

CHARLES N. BRISCO, OF CHICAGO, ILLINOIS.

BOTTLE-STOPPER.

SPECIFICATION forming part of Letters Patent No. 623,304, dated April 18, 1899.

Application filed July 15, 1898. Serial No. 686,016. (No model.)

To all whom it may concern:

Be it known that I, CHARLES N. BRISCO, a citizen of the United States, residing at Chicago, in the county of Cook and State of Illinois, have invented a new and useful Improvement in Bottle-Stoppers, of which the following is a specification.

This invention relates to improvements in stoppers for bottles or other receptacles of the class employed more especially as original receptacles or packages for special kinds of liquid merchandise to render the bottle non-refillable, and thus prevent such second or repeated use thereof by unauthorized persons as would enable them to refill the bottle and on the strength of the known guarantee of the bottle itself deceive users into the belief that the substitute contents were supplied by the original bottlers.

My object is to provide a simple and inexpensive bottle-stopper which while permitting original contents to be readily poured from the bottle will by preventing refilling of the bottle operate as an effective safeguard against use of the bottle a second time without such injury to the parts of the stopper as will lead to easy detection.

In the drawings, Figure 1 is a sectional view of the neck portion of a bottle with my improvements in place and showing the stopper closed; Fig. 2, a view similar to Fig. 1, but showing the stopper open to permit pouring of contents from the bottle; Fig. 3, a top plan view of the valve; Fig. 4, a perspective view, on a reduced scale, of a housing-piece forming one of the details of construction; Fig. 5, a view in elevation of a spring and spring-holder; Fig. 6, an elevation of the parts shown in Fig. 5, taken from another side; Fig. 7, a bottom plan view of a shield for the mouth of the bottle, forming part of the stopper construction; Fig. 8, a side elevation of the part shown in Fig. 7; Fig. 9, a wire locking-piece employed to secure the stopper against opening in transit; Fig. 10, a bottom plan view of the handle for opening and closing the valve; Fig. 11, a broken and partly-sectional elevation of the upper part of the stopper, and Fig. 12 a plan view of a blank or seal employed with the stopper as an additional safeguard.

A is the mouth or neck portion of a bottle. Crowded into and preferably cemented in place in the neck A in the position shown is a ring B, which may be of cork, provided with 55 the central opening t, surrounded by a valve-seat t'.

C is a shield or cap having a flat upper face s and provided on its underside with a downward-projecting tubular portion or sleeve s', 60 having preferably three radial projections or lugs s². The under face of the cap-piece C is formed with radial serrations presenting attaching parts s³ and an annular series of outlets s⁴. In practice the shield or cap-piece C rests at the parts s³ upon the upper end of the bottle, the parts s³ being recessed, as indicated at s⁵, to fit snugly over the annular end at the mouth of the bottle. The lugs or projections s² fit closely against the 70 inner wall of the neck portion of the bottle, as shown. To secure the shield or cap-piece in place, I provide a cement which will be unaffected by moisture and which will secure the parts firmly together. For bottles of different sizes I provide cap-pieces C to correspond and fit snugly in place. Extending through the sleeve portion s' is the central opening s⁶, flanked by vertical grooves or recesses s⁷. The upper face portion of the cap-piece is recessed around the opening s⁶ to produce an annular shallow socket s⁸. The lower end of the sleeve portion s' is shaped to form a pair of segmental cams s⁹, which commence at 80 and are deepest at the grooves s⁷. 85

D is a disk or handle having a flat under surface to fit closely against the upper surface of the cap-piece C and having a central stem r, which passes downward through the opening s⁶ in the sleeve s'. In the socket s⁸ 90 and confined between the cap C and disk D, around the stem r, is a spring r'. On the lower end portion of the stem r are radially-extending pins or lugs r², which when the stem is inserted through the opening s⁶ enter and pass through the grooves s⁷. The stem r is of such length that when inserted to a position where the disk D is close to but out of contact with the top of the cap-piece C, as shown in Fig. 2, the pins r² are just below the lower ends of the sockets s⁷. Turning 95 of the disk D causes the pins r² to slide 100

upon the cams s^9 and draw the disk D to the surface of the cap-piece C against the resistance of the spring r' , as shown in Fig. 1.

D' is a valve shaped at its underside to fit 5 the valve-seat t' and provided at its upper side with a circumferential recess q and preferably three upward-projecting guide-lugs q' .

D² is a housing-piece having an enlarged 10 lower end portion p to fit closely the annular groove q of the valve and having an upward-extending reduced sleeve portion p' , fitting over the lower end of the stem r in an inner annular socket s^{10} in the lower end portion of the sleeve s' . In the sleeve portion p' of the 15 housing-piece are bayonet-sockets p^2 , which receive the pins r^2 on the stem r , whereby the parts D² D are held together. In the top of the part p of the housing-piece around the sleeve portion p' is a series of openings p^3 , 20 and in the sleeve p' , just above the part p , is an internal annular shoulder or socket p^4 . In the upper side of the valve D' is a central 25 socket q^2 .

D³ is a spring lock or holder formed, 30 preferably, of a strip of flat springy metal and bent to produce the base n , shoulders $n' n^2$, inner sockets n^3 , and shoulders n^4 . Surrounding the spring-holder D³, between the shoulders $n' n^2$, is a confined helical spring D⁴, and 35 held in the sockets n^3 is a tablet, disk, or body D⁵ of a solvent material. The tablet D⁵ holds the jaws of the spring-holder D³ apart, whereby the shoulders n^4 fit the annular groove p^4 in the housing-piece D². On removal or dis- 40 integration of the tablet D⁵ the jaws of the spring-holder tend by their resilience to approach each other, release the shoulders n^4 from the annular sockets p^4 , and release the spring D⁴ from confinement by the shoulders 45 n^2 , whereby it will expand upward against the lower end of the stem r and press the valve D' to the seat t' .

The parts are placed in position in a bottle 50 after the latter has been filled with the liquid. The ring or cork B is first passed into the neck of the bottle, positioned, and preferably cemented in place. The disk or handle D and cap-piece C are put together by passing the stem r through the opening s^6 with the 55 spring r' between them. The spring-holder D³ is cemented or otherwise secured in the socket q^2 of the valve and the housing-piece D² placed upon the valve and secured thereto by springing the shoulders n^4 of the spring-holder into the socket p^4 . The housing, with the valve thus attached thereto, is then fastened at its bayonet-sockets to the pins r^2 and held thereby securely.

In practice the stem r should be cemented 60 or otherwise rigidly fastened to the sleeve portion p' of the housing-piece, so that they will always turn together and whereby they will be held against separation. The cap-piece C, with the valve and disk D, carried 65 thereby, is then passed into the mouth of the bottle and cemented in place at the surfaces s^5 and surfaces of the lugs q' , the parts being

in such relation that when the handle is turned to press the valve D' down the latter will seat upon the cork B and form a liquid-tight closure for the bottle. When it is desired to withdraw liquid contents from the bottle, the handle or disk D is turned, whereby the pins r^2 slide up the cams s^9 under the resilient action of the spring r' to raise the 70 disk D from the cap-piece C, and thus raise the valve D' from its seat. As the bottle is upset the liquid runs through the opening t and passage about the valve, housing-piece, and sleeve s' and out through the openings 80 s^5 between the cap-piece and the upper end of the bottle.

The housing-piece D² with the valve D' together form a housing-chamber p^5 , closed against the passage of liquid at all parts except at the openings p^3 , which are purposely small. None of the liquid escaping from the bottle as it is poured will enter through the openings p^3 , so that the tablet or body D⁵, of soluble material, will be shielded against contact therewith of the liquid. When any attempt is made to refill the bottle either by immersing it in liquid or pumping it in, the back pressure of air in the bottle will cause liquid to rise around the housing-piece and work its way into the chamber p^5 and by contacting with the soluble material D⁵ disintegrate the same, thereby releasing the spring-holder and spring D⁴ and causing the latter to expand against the lower surface of the 95 stem r and press the valve D' permanently to its seat. When this has occurred, the raising and lowering of the disk D and stem r will not affect the valve, which by remaining closed will prevent any more liquid from being 100 passed into the bottle or any that may have entered the bottle from being poured therefrom.

The gist of my invention lies in providing 110 within the passage through the neck of the bottle a chamber containing a valve-closing spring and held out of its valve-closing position by the tablet, block, or body of solvent material, the chamber being in open communication with the passage through one or more 115 ports which are out of the path of the liquid as it escapes from the bottle, but in position to receive liquid when the same is poured into the mouth of the bottle. As liquid is poured 120 it exerts no pressure against the ports p^3 , so that the air confined in the chamber p^5 will tend to prevent any of the liquid from entering the chamber and wetting the tablet. On the other hand, when liquid is poured into the mouth of the bottle the pressure, as before 125 stated, of the air in the neck and body portion of the bottle causes the liquid to force its way into the chamber p^5 , and thus wet and disintegrate the tablet and release the spring to permanently close the valve.

The body or tablet D⁵ is compressed, preferably, into the disk form shown, and the material or compound of which it is formed should be one that will remain hard and in-

tact while dry and disintegrate quickly when subjected to moisture. If desired, the material employed for the tablet may be such that it will not affect deleteriously the liquid which

5 the bottle is designed to contain, or, if desired, it may have chemical properties which will tend to change the color or appearance of the liquid with which it contacts.

The disk D, stem r, cap-piece C, and valve 10 D' may be formed of glass. The housing-piece D² may be of glass, or it may be formed of celluloid or other suitable material which will be readily injured by heat to destroy its use or form. The cement I employ for 15 securing the cap-piece in place is one that will effectively withstand the action of moisture, and by employing material for the housing-piece D² which would be injured or destroyed by heat it would be impossible to remove and 20 replace the cap-piece and attendant parts without doing such damage thereto as would lead to ready detection.

As a further safeguard against removal of the cap-piece I provide a seal E, of metal foil 25 or other suitable material, consisting of a strip having a central portion m to fit upon the cap-piece and provided with an opening m' of the size of and registering with the socket s³ to extend around the spring r', open- 30 ings m² to register with openings s⁴, and leg portions m³. The central part m is cemented to the cap-piece C, and the legs m³ are cemented to the neck of the bottle, and while the seal will not interfere with the turning 35 40 of the disk or handle D or with the pouring of the liquid it will be broken in any attempt to remove the cap-piece from the bottle. As is customary where seals are employed, it may be stamped or marked with the private trademark or the like of the bottler.

To prevent danger of accidental turning of the disk D to open the bottle during shipment, I provide sockets l in opposite sides of the disk and corresponding sockets l' in opposite sides of the cap-piece C to register with the sockets l when the valve is closed. I also provide a wire locking-piece F, having a body portion k and legs k'. When passed or sprung 45 50 over the disk C, the legs k' will enter the sockets l' in the disk and cap-piece, and thus lock the disk against turning.

While I prefer to construct my improvements throughout as shown and described, they may be modified without departing from 55 the spirit of my invention as defined by the claims.

What I claim as new, and desire to secure by Letters Patent, is—

1. In a bottle-stopper, a valve, a valve-closing spring, a housing provided with ports admitting liquid thereinto when it is attempted to refill the bottle, and a solvent body or its equivalent within said housing normally holding said spring against action and protected 60 65 by the housing against liquid contact while the bottle contents are being poured out; said body being exposed to liquid contact when an

effort is made to refill the bottle and serving when disintegrated to release said spring to permit it to act to close the valve, substantially as described. 70

2. In a bottle-stopper, the combination with a valve-seat and valve at the base portion of the stopper, means for opening and closing the valve, an outlet for liquid toward the outer end of the stopper, and a passage for the liquid extending from the valve-seat to said outlet, of a chamber communicating with said passage, a valve-closing spring, a body of solvent material in said chamber holding the spring out of its valve-closing position and operating when disintegrated by contact with liquid to release the spring to seat the valve, substantially as and for the purpose set forth. 75 80 85

3. In a bottle-stopper, the combination of a cap-piece, to fit the mouth of the bottle, having a sleeve portion to extend into the neck of the bottle and form an outlet-passage for liquid about the sleeve portion, a valve-operating handle having a stem passing through said sleeve portion, a valve-seat in the neck of the bottle, a valve at the valve-seat, a housing-piece between the valve and stem forming a chamber communicating with said outlet-passage, a removable valve-attaching piece in said chamber securing the valve to the said stem, a valve-closing spring in said chamber, a body of solvent material in the chamber operating to hold the valve-attaching piece in valve-attaching position and the spring out of valve-closing position, whereby when the solvent material is disintegrated by contact with liquid the valve-closing spring is released and the valve-attaching 90 95 100 105 piece is disconnected, substantially as and for the purpose set forth.

4. In a bottle-stopper, the combination of a cap-piece, to fit the mouth of the bottle, having a sleeve portion to extend into the neck of the bottle and form an outlet-passage for liquid about the sleeve portion, a valve-operating handle having a stem passing through said sleeve portion, a valve-seat in the neck of the bottle, a valve at the valve-seat, a housing-piece between the valve and stem, of material readily susceptible to injury by heat, forming a chamber communicating with said outlet-passage, a removable valve-attaching piece in said chamber securing the valve to the said stem, a valve-closing spring in said chamber, a body of solvent material in the chamber operating to hold the valve-attaching piece in valve-attaching position and the spring out of valve-closing position, whereby 110 115 120 125 130 when the solvent material is disintegrated by contact with liquid the valve-closing spring is released and the valve-attaching piece is disconnected, substantially as and for the purpose set forth.

5. In a bottle-stopper, the combination of a cap-piece, to fit the mouth of the bottle having an opening through it, and having discharge-ports whereby liquid may pass from

the mouth, a handle having a stem passing through said opening in the cap-piece, a valve-seat in the bottle, a valve, and means connecting said valve rigidly to said stem to cause the valve to move positively up and down with the stem, said means being capable of disconnecting the valve from the stem

under the conditions specified and for the purpose set forth.

CHARLES N. BRISCO.

In presence of—

RICHARD T. SPENCER,
M. J. FROST.
